PUMP JACK

Louis Kessler, Oak Park, Ill., assignor to Charles J. Muntwyler, Oak Park, Ill.

Application November 18, 1943, Serial No. 510,783

2 Claims. (Cl. 74—46)

1

This invention relates to a pump jack which may be fitted to a farm pump of conventional type for the purpose of operating the pump either by power derived from a motor or from a windmill or by hand, and the invention is directed particularly to the means provided for compactly arranging the mechanical assembly so that it may be connected interchangeably, either to the reciprocating shaft of a windmill or to the rotating power take-off of an engine or motor and effectively apply the power thus derived to a reciprocating pump rod.

Further objects and details will appear from a description of the invention in conjunction with the accompanying drawing wherein—

Figure 1 is a sectional elevation of the pump jack mounted on a pump of conventional type; Fig. 2 is a side elevation of the pump jack; and Fig. 3 is a sectional detail taken on offset line 3—3 in Fig. 1.

The pump jack, as shown, is mounted upon a pump 10 terminating in a neck 11 which carries the standard 12 of the pump jack. The base of the standard encircles the neck of the pump and is held thereon by set screws 13, and a shim ring 14 may, if necessary, be interposed between the standard and the neck in cases where a tight fitting of the parts requires the use of one or more shim rings, thus adapting the jack for use on pumps having necks of varying diameters.

The standard at its upper end terminates in a cross head 15 to which is secured a housing 16 within which the operating parts are enclosed. The head has fitted thereto a sleeve 17 which furnishes a guide for a reciprocating stem 18 which is secured by a coupling 19 to the pump rod 20. The stem carries a rack 21 terminating in an extension 22, which is guided within a tubular cap 23 upstanding from the housing.

The rack meshes with a segment 24 carried by a sleeve 25, mounted on a pintle 26, and having rigidly secured thereto an arm 27 provided with a longitudinal slot 28 within which rides a roller 29, bearing against the face of the slotted arm. The roller is carried on a pin 30 which also carries the guiding washer or head 31 to ensure proper relationship between the pin and the arm. The pin is radially adjustable within a slot 32 in a segmental portion of a spur gear wheel 33, fixed on a stub shaft 34, journaled through the side wall of the housing and carrying at its outer end a crank arm 35.

The crank arm pivots the upper end of a link 36, the lower end of which is pivoted to the inner end of a lever 37, medially fulcrumed on a pin

2

38 and upturned at its outer end 39 to make connection, when desired, with the lower end of a reciprocating windmill shaft 40, which will impart rotation through the crank to the spur gear, thus oscillating the segment 24, which meshes with the rack connected with the pump rod.

Power is alternately derived from a rotating pulley (not shown) on a motor or engine which connects with a pulley 41 on shaft 42 journaled through the side walls of the housing, which shaft has slidably keyed thereon a pinion 43, having a grooved hub 44, engaged by the inner end of a pivoted clutch lever 45, which may be moved, either to engage the pinion with the gear wheel 33, or to break the engagement when it is desired to derive power from the windmill. In order to hold the teeth of the rack 21 into firm engagement with the teeth of the segment 24, the rack is backed by a guide arm 46, the foot 47 of which is screwed to a bracket 48 secured to the wall of the housing.

Operation

With the pinion 43 thrown out of mesh and the reciprocating windmill shaft 40 connected to lever 37, rotation will be imparted directly to the gear shaft and the rotation of the gear 33 will impart oscillating movements to the segment 24 through the slotted arm 27 and roller 29, thus reciprocating the rack. With the gear rotating clockwise in Fig. 1, the lifting stroke of the pump rod will begin with the roller 29 in the lower middle position and moving horizontally to the left. As the rotation of the gear continues, the vertical component of movement of the roller will increase to maximum at the medial position and thereafter decrease to zero when the roller reaches the top position shown in Fig. 1. Thus the speed of the pump stroke will alternately accelerate and retard as the rack reaches the limits of its range of movements so that no sudden reversals of movement will be imparted to the pump rod.

However, although the vertical component of movement of the roller 29 increases as the medial position is approached, its movement will be imparted to the oscillating shaft 26 and segment 24 through an increasingly longer section of the slotted arm 27, so that the movement imparted to the rack while travelling through the intermediate position, with corresponding reduction in power, will not be excessive at any stage in the stroke, but will be harmoniously proportioned to secure the most effective action. Furthermore, variations in the transmission of power at differ-

ent stages in the cycle can also be attained by adjusting the position of the roller 29 within the slot 32.

The return movement of the rack during the down stroke of the unloaded pump rod, will accelerate and retard more rapidly and in increased degree, owing to the reduction in the effective length of the slotted arm 27 as the roller 29 attains its nearest approach to the shaft 26 on which the arm is pivoted, but such increased acceleration and deceleration is unobjectionable at this stage, since the pump rod is unloaded and the parts are merely restored to active position.

When it is desired to derive power from an engine or motor shaft, the pinion 43 is thrown into mesh with the gear 33 which imparts reciprocating movements to the rack and pump rod through the train of connections in the manner heretofore described. Obviously, moreover, if occasion should require, the lever 27 can be operated manually instead of through power derived from the windmill.

The invention as a whole is of a nature which permits it to be fitted as a unit to any farm pump of standard type and to be operated in a manner which will effectively employ power derived either from a rotating element, as in the case of an engine or motor, or from a reciprocating element as in the case of a windmill shaft or the like.

I claim:

1. A pump jack adapted to be fitted to a farm pump and operable by either a motor or a windmill and comprising a housing adapted to be fitted to a pump having a vertically reciprocating pump rod, a vertically slideable rack bar adapted to be connected to the pump rod, an oscillating gear element meshing with the rack bar and pivotally mounted at one side of the same, an arm fixed to the gear element and adapted to operate in unison therewith and provided with a longitudinal slot, a rotating gear element mounted in the housing and having its axis spaced from that of the oscillating gear element, a crank carried by the oscillating gear element and operable in the slot of said arm, a horizontal crank shaft journaled in the housing and connected with said rotating gear element and operable in the slot of said arm, a lever fulcrumed intermediate of its ends and extending beyond the housing, a link connecting one arm of the lever with said crank arm, means for detachably connecting the other end of the lever with a reciprocating actuating member of the windmill, and means for connecting the rotating gear element with a motor and for disconnecting it therefrom including a pinion meshing with said rotating gear element.

the rotating gear element and operable in the slot of said arm, a horizontal crank shaft journaled in the housing and connected with said rotating gear element and provided with a crank arm, a lever fulcrumed intermediate of its ends and extending beyond the housing, a link connecting one arm of the lever with said crank arm, means for detachably connecting the other end of the lever with a reciprocating actuating member of the windmill, and means for connecting the rotating gear element with a motor and for disconnecting it therefrom including a pinion meshing with said rotating gear element.

2. A pump jack adapted to be fitted to a farm pump and operable by either a motor or a windmill and comprising a housing adapted to be fitted to a pump having a vertically reciprocating pump rod, a vertically slideable rack bar adapted to be connected to the pump rod, an oscillating gear element meshing with the rack bar and pivotally mounted at one side of the same, an arm fixed to the gear element and adapted to operate in unison therewith and provided with a longitudinal slot, a rotating gear element mounted in the housing and having its axis spaced from that of the oscillating gear element, a crank carried by the rotating gear element and operable in the slot of said arm, a horizontal crank shaft journaled in the housing and connected with said rotating gear element and provided with a crank arm, a lever fulcrumed intermediate of its ends and extending beyond the housing, a link connecting one arm of the lever with said crank arm, means for detachably connecting the other end of the lever with a reciprocating actuating member of the windmill, a driving shaft journaled in the casing, a gear fixed to the driving shaft and meshing with the rotating gear element, a pulley adapted to be connected with and actuated by a motor, and means including a clutch for connecting the pulley with the driving shaft and for disconnecting it therefrom.

LOUIS KESSLER.
